PICKER SPINDLE LUBRICATOR

Robert S. Schedin, Worcester, Mass., assignor to
Crompton & Knowles Loom Works, Worcester,
Mass., a corporation of Massachusetts

Application June 15, 1945, Serial No. 599,621

3 Claims. (Cl. 139—158)

1

This invention relates to improvements in lubricators for loom picker spindles and it is the general object of the invention to provide simple means by which the spindle will be lubricated due to motion of the lay.

The picking mechanism of certain types of looms employs a long slender picker spindle secured to the lay behind the shuttle box and along which the picker is driven by the picker stick. In order to provide smooth running for the shuttle it is necessary to lubricate the spindle so that the picker will slide along it easily. It is an important object of my present invention to provide a lubricating device mounted on the loom and having a depending rod or wire which is struck by the spindle as the lay approaches back center and is tilted slightly to open a valve normally held against its seat by a spring within the reservoir. When the valve is unseated a small amount of oil drips down on the wire and is passed from the latter to the spindle.

Loom lays are customarily driven by a crank shaft which completes a rotation each pick of the loom and moves the lay between front and back positions during loom operation. The picking stroke for the shuttle customarily occurs when the lay is on so-called top center and about midway between its front and back positions while moving rearwardly. At some time prior to arrival of the lay at its rearmost position the picker is ordinarily on its return stroke and it is a further object of the invention to mount the aforesaid reservoir and lubricator wire so that the latter will engage the spindle near its inner end after the picker has started its return stroke.

Although the picker ordinarily operates as already described, conditions can nevertheless develop in a loom which will cause the picker to be in its inmost position when the lay is at back center, or be in motion toward the outer end of the spindle when in register with the lubricator wire. In order that no damage may be done to the wire under these conditions it is so made as to be capable of universal angular movement with respect to the reservoir.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a portion of a loom having my invention applied thereto, parts of the lay and the shuttle being shown in section.

Fig. 2 is an enlarged vertical section through the lubricator reservoir, the picker spindle and lay being shown in two positions and the lay being in section.

Fig. 3 is an enlarged vertical section of the low-

2

er part of the reservoir shown in Fig. 2 indicating how tilting of the wire unseats the valve,

Fig. 4 is an enlarged plan view looking in the direction of arrow 4, Fig. 1, showing the lay in forward position and indicating the manner in which the reservoir can be adjusted with respect to the loom frame, and

Figs. 5 to 7 are diagrammatic views showing the mode of operation of the invention.

10 Referring particularly to Fig. 1, the loom frame 10, top or crank shaft 11, lay 12 and lay connector 13 may be of usual construction. The lay is provided with a shuttle box 14 to receive the shuttle S, and a picker spindle 15 is secured to the lay and extends along the latter behind and substantially parallel to the shuttle box. A picker 16 slides on the spindle 15 and extends to the left as viewed in Fig. 4 to have its forward end 17 in engagement with the tip of the shuttle S. The picker stick 18 extends through a slot 19 in the picker and is the means by which the latter is propelled along the spindle.

In the matter thus far described rotation of the crank shaft 11 in a clockwise direction as viewed

25 in Fig. 1 causes the lay 12 to reciprocate backwardly and forwardly, and the picker stick ordinarily has its picking or working stroke when the lay is moving rearwardly and is about midway between its front and back extreme positions.

30 During the picking stroke the picker 16 slides along the spindle toward the center of the loom, or up as viewed in Fig. 4, to cause the shuttle propelling end 17 to pick the shuttle toward the opposite side of the loom. On completion of the

35 picking stroke the picker stick moves outwardly to slide the picker 16 on its return stroke in an outward direction along the spindle, or downwardly as viewed in Fig. 4. Ordinarily the picker 16 will have completed a part of its return stroke by the time the lay reaches its rearmost position.

In carrying my present invention into effect I provide a simple lubricator for the spindle 15. The lubricator includes a bracket 25 secured to the loomside and having a slot 26, see Fig. 4,

40 which extends generally in the direction toward and from the loomside and parallel to the lay and picker spindle. A clamp arm 27 is slotted as at 28, and a bolt 29 passes through the two slots and is the means by which the arm 27 can be held in adjusted and fixed position with respect to the loom and bracket 25. The outer end of the arm 27 is provided with a circular strap 30 which surrounds a cylindrical oil reservoir 31. A screw 32 clamps the strap 30 against the reservoir to hold

45 the latter in vertically adjusted position. It will be seen therefore that the cylinder can be adjusted toward and from the front of the loom, toward the loom frame 10, and vertically.

The reservoir 31 is provided with a cap 35 having an inlet 36 by means of which a lubricant

such as oil can be introduced into the reservoir. A long compression spring 37 presses upwardly against the cap 35 and extends for the length of the cylinder and bears against a valve 38 which may have a recess 39 to receive the lower end of the spring.

Secured to the valve 38 is a lubricator rod or wire 40 which extends downwardly through an opening or discharge port 41 in the bottom wall 42 of the reservoir cylinder 31. The hole 41 is 10 preferably slightly larger in diameter than the lubricator element or rod 40 so that the latter can move from the full to the dotted line position shown in Fig. 3. If desired a washer 43 formed of suitable material may be secured to the under side of the valve 38. The rod 40 extends downwardly and may be rounded as at 45 and be so located that it will be engaged by the picker spindle 15 as the lay moves rearwardly. The rod 40 is preferably located near the inner end 15 of the spindle 15 so that it engages the latter after the picker 16 has started on its outward return stroke.

The operation of the invention is illustrated in Figs. 2 and 5 to 7. When the lay is on front center position as indicated in full lines in Fig. 2 and in Fig. 5 the spindle 15 will be in forward position and spring 37 will hold rod 40 in normal substantially vertical position with the valve 38 closing the hole 41. As the crank shaft turns in a clockwise direction it will assume the position shown in Fig. 6 as the lay approaches its back center position, and cause spindle 15 to engage the lower end of rod 40. Further rearward movement of the lay to the back center position shown in Fig. 7 will cause a slight displacement of rod 40 to the position indicated in Fig. 3, whereupon a small amount of oil will pass under the valve 38 and into the hole 41 and thence to the rod 40. The oil thus released will move down the rod 40 and eventually reach the lower curved end thereof which is struck by the spindle and be transferred to the latter. As soon as the lay starts to move forwardly from the position shown in Fig. 7 the spring 37 will return the rod 40 from the dotted to the full line position shown in Fig. 2, and also seat the valve 38 to prevent leakage of oil.

The valve 38 is preferably circular so that it can tip in any angular direction with respect to the bottom 42 of the reservoir. It is because of this shape of the valve that the rod 40 can be deflected not only as indicated in dotted lines in Figs. 2 and 3, but can also move in a direction parallel to the spindle 15, should the lower end of the rod be improperly engaged by the picker when it is moving along the spindle 15.

From the foregoing it will be seen that I have provided simple picker spindle lubricator mechanism including a lubricator rod mounted for universal motion with respect to a lubricator cylinder and having at the upper end thereof a valve which normally is seated to prevent escape of oil through the hole 41. It will also be seen that the cylinder 30 may be adjusted vertically, or backwardly and forwardly, or inwardly and outwardly with respect to the loomside 10. The spring 37 serves not only to seat the valve but also restores the wire 40 to its normal position.

Having thus described my invention it will be seen that changes and modification may be made therein by those skilled in the art without depart-

ing from the spirit and scope of the invention and I do not wish to be limited to the details herein disclosed, but what I claim is:

1. In lubricator mechanism for a picker spindle mounted on a substantially horizontally reciprocating lay and along which a picker slides, a lubricant reservoir held in fixed position and having in the bottom thereof a port for the discharge of lubricant, a valve over said port so proportioned relatively to the reservoir as to be tiltable relatively to the bottom of the reservoir, a spring within the reservoir normally holding the valve seated over the port, and a lubricant rod secured to the valve and extending downwardly through said port and into the path of the spindle, said rod being of a size to permit lateral motion thereof within the port, reciprocation of the lay causing the spindle to engage said rod to tilt the latter and said valve with respect to the reservoir and open the valve to permit lubricant to pass from the reservoir through said port onto said rod.

2. In lubricator mechanism for a picker spindle mounted on a substantially horizontally reciprocating lay and along which a picker slides, a fixed lubricant reservoir located above and behind the lay and having a lubricant discharge port in the under side thereof, a circular valve over said port, a spring within the reservoir normally holding said valve seated over the port to prevent discharge of lubricant, and a lubricating element secured to the valve and passing through the port and extending downwardly into the path of the spindle and picker, said valve and element constituting a unit capable of tilting in any angular direction relatively to the reservoir, engagement of the element by either the spindle or the picker tilting said element and the valve relatively to the reservoir to permit lubricant within the reservoir to move downwardly from the port and onto said element.

3. In lubricator mechanism for a picker spindle of a loom having a reciprocating lay along which a picker slides, a bracket secured to and projecting from the loom in a direction substantially parallel to the length of the lay and having a slot therein extending toward and from the loom, a strap member, securing means passing through the bracket and strap member to hold the latter at any one of a plurality of positions with respect to the strap and the loom, a vertically extending lubricant reservoir within said strap, means to clamp said strap to the reservoir when the latter is in any one of a plurality of vertical positions, and a lubricating element communicating with the interior of the reservoir and depending therefrom into the path of the spindle.
